COMBINED SAFETY RAZOR AND
HAIRCUTTER

Michael Verdi, Jamaica, N. Y.

Application August 19, 1950, Serial No. 180,465

9 Claims. (Cl. 30—30)

1

This invention relates to tonsorial implements and, more particularly, to a combined safety razor and hair cutter.

One object of the invention is the provision of a combined safety razor and hair cutter whereby all of the grooming operations ordinarily performed by a barber in his shop may be performed by the individual within the confines of his home.

Another object of the invention is to construct the device so that the hair cutting and the shaving portions thereof are extremely effective and yet absolutely safe.

Still another object of the invention is to construct the device so that the cutting means although normally locked in place are readily removed and replaced.

A further object of the invention is to construct the device so that the same is capable of being manufactured economically.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure.

Fig. 1 is a side elevational view of the device of the invention.

Fig. 2 is a bottom view of the device.

Fig. 3 is an isolated isometric view of the handle portion of the device.

Fig. 4 is an isolated perspective view of the shaving and hair cutting portion of the device.

Fig. 5 is an exploded perspective view of means for connecting the two portions of the device.

Fig. 6 is a plan view of the hair cutting and shaving portion shown in Fig. 4.

Fig. 7 is a face view of the cutting means.

Fig. 8 is an enlarged fragmentary sectional view on line 8—8 of Fig. 1.

Fig. 9 is an enlarged sectional view on line 9—9 of Fig. 1.

Fig. 10 is a side elevational view similar to Fig. 1, but illustrating the device constructed in accordance with a modification of the present invention.

Fig. 11 is an enlarged partial longitudinal sectional view taken on the line 11—11 of Fig. 10.

The combined safety razor and hair cutter, according to the first form of the present invention shown in Figs. 1 to 9, includes a handle 10 of tapering width which may be provided with a comb having a plurality of tines or teeth 11 and a back-
ing member 12, see particularly Figs. 1, 2 and 3.

2

Preferably the handle is formed of a clear plastic material. The hair cutting and shaving portion of the device preferably is formed separate from the handle 10 so that the latter may conveniently be replaced if one or more of the teeth 11 are broken. The said cutting and shaving portion comprises a plastic bar 13 having slightly convex side faces, see also Figs. 4 and 6. One edge of bar 13 is provided with ridges or serrations 14 and the other edge is provided with short teeth or tines 15. Before describing further the shaving and cutting portion of the device it is deemed desirable first to describe the manner in which the same is attached to handle 10.

5 The wider end edge of handle 10 is provided at one side thereof with a semicircular extrusion or extension 16 of substantially half the thickness of the edge. The said extension is formed into a circle by a semicircular notch 17 in the opposite side of said edge, said notch having a depth equal to half the thickness of the edge. One end edge of bar 13 is provided with an extension 18 and a notch 19 like in all respects to the extension 16 and notch 17 except that they are oppositely disposed relative to the two sides of the device, see Figs. 3, 4, 6 and 8. The construction is such that the notches and extensions complement one another and extension 18 fits into notch 17 while extension 16 fits into notch 19. To secure the parts together a hole 21 is provided at the center of each of the said circles and a sleeve 22 is passed through the two. Passing through the sleeve 22 is a tapered head bolt 23 which is threaded into a circular tapered nut 24, see also Fig. 5. The bolt 23 also passes through a pair of retainer washers 25 to be more fully described hereinafter, the holes in said washers being countersunk to receive said tapered nut and the tapered head of the bolt.

30 It is believed evident, therefore, that the construction just above described provides an effective, readily manipulated connection between bar 13 and comb 10.

35 As mentioned above, the side faces of bar 13 are slightly convex, and each said face has projecting therefrom a pair of longitudinally spaced studs or lugs 26. The said lugs are adapted to engage in the usual slots 27 arranged along the longitudinal center line of an ordinary double edge safety razor blade 28 such as that illustrated in Fig. 7. It will be seen, therefore, that a blade 28 is mounted on either face of said bar by means of the lugs 26.

40 The serrations 14 and the teeth 15 project past the edges of the blades 28 and serve to space said

55

edges from the skin, the former in shaving and the latter in hair cutting. However, an exterior guard is required for each blade 28. To this end, the free end edge of bar 13 is provided with a cutout 30 whose end walls are provided each with a shallow well or indentation 31 as best shown in Fig. 9. Mounted in the said wells and extending across cutout 30 is a rod 32 which preferably is forced into place but has a loose fit when engaged in said wells. A pair of cover or guard plates 33 are provided, one on either side of bar 13, each plate having formed off from the end thereof a tail 34 which is wound about the rod 32. Thus, the said plates are pivoted on said rod. Each guard plate 33 is in the form of a shallow trough whose end walls fit over the ends of the blades 28, and whose side edges leave exposed only the very edges of said blades, see Figs. 1 and 4.

It is desired that the guards 33 normally be locked in the guarding position of Fig. 1, but be swingable on their pivots to the position of Figs. 4 and 6 to remove and replace the blades 28. To this end the free end wall of each guard is extended at its center as at 35 and has secured thereto an inverted L-shaped member 36, see also Fig. 8.

To accommodate the said extension and the upright portion of the inverted L-shaped member 36 the face of bar 13 is provided with a well 37. It will readily be perceived that when said parts are engaged in said well, the guard 33 is locked against lateral movements. To prevent pivotal movements of the guards the cross bar of each L-shaped member 36 extends along the surface of bar 13 beneath a bent-up tail 38 formed on the associate retainer washer 25 hereinbefore described. Thus, when the bolt 23 is drawn up the said tails secure the guards 33 in guarding position. However, the bolt can be loosened to allow the washers to be turned, thus disengaging the said tails 38 from the inverted L-shaped members and freeing the latter.

The construction is such that with the guards 33 in locked position the serrations 14 space the edges of the blades 28 an extremely short distance from the face so that a close shave may be obtained in safety; and the teeth 15 space the edges of said blades a greater distance from the skin for effectively trimming the hair.

In the modification of the present invention shown in Figs. 10 and 11, the tapered handle 10' and the bar 13' are formed of one piece of resinous plastic material. The juncture of the handle 10' and the bar 13' is formed with a hole 21' for the passage of the bolt 23' to mount the retainer washers 25 in position upon the sides of the device. In view of the one-piece construction of the handle 10' and the bar 13', the sleeve 22, used in the first form of the invention, has been eliminated.

In all other respects, the form of the invention shown in Figs. 10 and 11 is similar to the first form and like reference numerals identify like parts.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A combined safety razor and hair cutter which comprises a plastic handle of tapering width, a semicircular extension projecting from one side of the wider end edge of the handle and of half the thickness of the edge, a semicircular cutout in the other side of the edge aligned with and extending down to said extension to form a circular portion of half the thickness of the handle, a hole in the center of said circle, a plastic bar, a semicircular extension on one end edge of said bar identical with the first said extension but oppositely disposed, a semicircular notch in the edge of the bar and forming with the extension a circular portion of half the thickness of the bar, a hole in the last said circular portion, the two said circular portions being aligned with one another in abutting relationship, a sleeve passed through said holes, a taper head bolt passed through said sleeve, a tapered nut on said bolt, a pair of washers mounted one on either end of the bolt, a countersunk hole in each said washer to receive the tapered head of the bolt or the tapered nut, teeth on one side edge of said bar, serrations on the other side edge of the bar, a pair of longitudinally spaced lugs projecting from either face of the bar and adapted to receive a double edge safety razor blade mounted on each pair of lugs with the cutting edges of said blades in operative relation with said teeth and said serrations, a pair of guard members pivotally connected to said bar and adapted to cover all save the cutting edges of said safety razor blades, and means connected to said bar for locking each said member in covering position.
2. A combined safety razor and hair cutter which comprises a plastic handle of tapering width, a semicircular extension projecting from one side of the wider end edge of the handle and of half the thickness of the edge, a semicircular cutout in the other side of the edge aligned with and extending down to said extension to form a circular portion of half the thickness of the handle, a hole in the center of said circle, a plastic bar, a semicircular extension on one end edge of said bar identical with the first said extension but oppositely disposed, a semicircular notch in the edge of the bar and forming with the extension a circular portion of half the thickness of the bar, a hole in the last said circular portion, the two said circular portions being aligned with one another in abutting relationship, a sleeve passed through said holes, a taper head bolt passed through said sleeve, a tapered nut on said bolt, a pair of washers mounted one on either end of the bolt, a countersunk hole in each said washer to receive the tapered head of the bolt or the tapered nut, teeth on one side edge of said bar, serrations on the other side edge of the bar, a pair of longitudinally spaced lugs projecting from either face of the bar and adapted to receive a double edge safety razor blade mounted on each pair of lugs with the cutting edges of said blades in operative relation with said teeth and said serrations, a pair of guard members pivotally connected to said bar and adapted to cover all save the cutting edges of said safety razor blades, and means connected to said bar for locking each said member in covering position.
3. A combined safety razor and hair cutter which comprises a plastic handle of tapering width, a semicircular extension projecting from

one side of the wider end edge of the handle and of half the thickness of the edge, a semicircular cutout in the other side of the edge aligned with and extending down to said extension to form a circular portion of half the thickness of the handle, a hole in the center of said circle, a plastic bar, a semicircular extension on one end edge of said bar identical with the first said extension but oppositely disposed, a semicircular notch in the edge of the bar and forming with the extension a circular portion of half the thickness of the bar, a hole in the last said circular portion, the two said circular portions being aligned with one another in abutting relationship, a sleeve passed through said holes, a taper head bolt passed through said sleeve, a tapered nut on said bolt, a pair of washers mounted one on either end of the bolt, a countersunk hole in each said washer to receive the tapered head of the bolt or the tapered nut, teeth on one side edge of said bar, serrations on the other side edge of the bar, a pair of longitudinally spaced lugs projecting from either face of the bar and adapted to receive a double edge safety razor blade mounted on each pair of lugs with the cutting edges of said blades in operative relation with said teeth and said serrations, a cutout in the other end edge of the bar, an indenture in each side wall of said cutout, a rod mounted in said indentures, a pair of guard members one on either side of the bar, each member having a tail pivoted on said rod, each member covering all save the cutting edges of said safety razor blades and comprising a shallow trough, an extension projecting toward the bar from the free end of each member, a well in each face of the bar to receive said extension, and means connected to said bar for locking said extensions in said wells.

4. A combined safety razor and hair cutter which comprises a plastic handle of tapering width, a semicircular extension projecting from one side of the wider end edge of the handle and of half the thickness of the edge, a semicircular cutout in the other side of the edge aligned with and extending down to said extension to form a circular portion of half the thickness of the handle, a hole in the center of said circle, a plastic bar, a semicircular extension on one end edge of said bar identical with the first said extension but oppositely disposed, a semicircular notch in the edge of the bar and forming with the extension a circular portion of half the thickness of the bar, a hole in the last said circular portion, the two said circular portions being aligned with one another in abutting relationship, a sleeve passed through said holes, a taper head bolt passed through said sleeve, a tapered nut on said bolt, a pair of washers mounted one on either end of the bolt, a countersunk hole in each said washer to receive the tapered head of the bolt or the tapered nut, teeth on one side edge of said bar, serrations on the other side edge of the bar, a pair of longitudinally spaced lugs projecting from either face of the bar and adapted to receive a double edge safety razor blade mounted on each pair of lugs with the cutting edges of said blades in operative relation with said teeth and said serrations, a cutout in the other end edge of the bar, an indenture in each side wall of said cutout, a rod mounted in said indentures, a pair of guard members one on either side of the bar, each member having a tail pivoted on said rod, each member covering all save the cutting edges of said safety razor blades and comprising a shallow trough, an extension projecting toward the bar from the free end of each member, a well in each face of the bar to receive said extension, an L-shaped member secured to each of the last said extensions, and a tail formed on each said washer to engage the associated L-shaped member and lock the said extension in said wells, whereby on loosening said bolt the tails of said washers can be turned out of engagement with said L-shaped members to free said guard members.

5. A combined safety razor and hair cutter which comprises a handle of tapering width, a bar connected to and extended longitudinally from the wider end edge of the handle, teeth on one side edge of said bar, serrations on the other side edge of the bar, a pair of longitudinally spaced lugs projecting from either face of the bar and adapted to receive a double edge safety razor blade mounted on each pair of lugs with the cutting edges of said blades in operative relation with said teeth and said serrations, a pair of guard members pivotally connected to said bar and covering all save the cutting edges of said blades, and means connected to said bar for locking each member in covering position, said handle and said bar being separate pieces with adjacent ends connected together.

shallow trough, an extension projecting toward the bar from the free end of each member, a well in each face of the bar to receive said extension, an L-shaped member secured to each of the last said extensions, and a tail formed on each said washer to engage the associated L-shaped member and lock the said extensions in said wells.

6. A combined safety razor and hair cutter which comprises a plastic handle of tapering width, a semicircular extension projecting from one side of the wider end edge of the handle and of half the thickness of the edge, a semicircular cutout in the other side of the edge aligned with and extending down to said extension to form a circular portion of half the thickness of the handle, a hole in the center of said circle, a plastic bar, a semicircular extension on one end edge of said bar identical with the first said extension but oppositely disposed, a semicircular notch in the edge of the bar and forming with the extension a circular portion of half the thickness of the bar, a hole in the last said circular portion, the two said circular portions being aligned with one another in abutting relationship, a sleeve passed through said holes, a taper head bolt passed through said sleeve, a tapered nut on said bolt, a pair of washers mounted one on either end of the bolt, a countersunk hole in each said washer to receive the tapered head of the bolt or the tapered nut, teeth on one side edge of said bar, serrations on the other side edge of the bar, a pair of longitudinally spaced lugs projecting from either face of the bar and adapted to receive a double edge safety razor blade mounted on each pair of lugs with the cutting edges of said blades in operative relation with said teeth and said serrations, a cutout in the other end edge of the bar, an indenture in each side wall of said cutout, a rod mounted in said indentures, a pair of guard members one on either side of the bar, each member having a tail pivoted on said rod, each member covering all save the cutting edges of said safety razor blades and comprising a shallow trough, an extension projecting toward the bar from the free end of each member, a well in each face of the bar to receive said extension, an L-shaped member secured to each of the last said extensions, and a tail formed on each said washer to engage the associated L-shaped member and lock the said extension in said wells, whereby on loosening said bolt the tails of said washers can be turned out of engagement with said L-shaped members.

7. A combined safety razor and hair cutter which comprises a handle of tapering width, a bar connected to and extended longitudinally from the wider end edge of the handle, teeth on one side edge of said bar, serrations on the other side edge of the bar, a pair of longitudinally spaced lugs projecting from either face of the bar and adapted to receive a double edge safety razor blade mounted on each pair of lugs with the cutting edges of said blades in operative relation with said teeth and said serrations, a pair of guard members pivotally connected to said bar and covering all save the cutting edges of said blades, and means connected to said bar for locking each member in covering position, said handle and said bar being separate pieces with adjacent ends connected together.

7. A combined safety razor and hair cutter which comprises a handle of tapering width, a bar connected to and extended longitudinally from the wider end edge of the handle, teeth on one

side edge of said bar, serrations on the other side edge of the bar, a pair of longitudinally spaced lugs projecting from either face of the bar and adapted to receive a double edge safety razor blade mounted on each pair of lugs with the cutting edges of said blades in operative relation with said teeth and said serrations, a pair of guard members pivotally connected to said bar and covering all save the cutting edges of said blades, and means connected to said bar for locking each member in covering position, said handle and said bar being separate pieces with adjacent ends connected together, said connection of said handle and said bar being a releasable one so that said parts can be separated when desired.

8. A combined safety razor and hair cutter which comprises a handle of tapering width, a bar connected to and extended longitudinally from the wider end edge of the handle, teeth on one side edge of said bar, serrations on the other side edge of the bar, a pair of longitudinally spaced lugs projecting from either face of the bar and adapted to receive a double edge safety razor blade mounted on each pair of lugs with the cutting edges of said blades in operative relation with said teeth and said serrations, a pair of guard members pivotally connected to said bar and covering all save the cutting edges of said blades, and means connected to said bar for lock-

ing each member in covering position, said handle and said bar being of one-piece construction.

9. A combined safety razor and hair cutter which comprises a handle of tapering width, a bar connected to and extended longitudinally from the wider end edge of the handle, teeth on one side edge of said bar, serrations on the other side edge of the bar, a pair of longitudinally spaced lugs projecting from either face of the bar and adapted to receive a double edge safety razor blade mounted on each pair of lugs with the cutting edges of said blades in operative relation with said teeth and said serrations, a pair of guard members pivotally connected at one of their ends to said bar and covering all save the cutting edges of said blades, and means connected to said bar for locking each said member in covering position.
